CAP FOR A CONTAINER

Vincenzo Pomodoro, Rome, Italy, assignor to Neotis
S.p.A., Como, Italy, a corporation of Italy

Filed Dec. 6, 1968, Ser. No. 14,831

Claims priority, application Italy Oct. 1, 1968

Term of patent 7 years

Int. Cl. D9—02

U.S. Cl. D9—282

FIG. 1.

FIG. 4.

FIG. 2.

FIG. 3.

FIG. 1 is a front elevational view of a cap for a container showing my new design;

FIG. 2 is an elevational view looking from the right of FIG. 1;

FIG. 3 is a top plan view thereof; and

FIG. 4 is a rear elevational view thereof.

I claim:

The ornamental design for a cap for a container, substantially as shown.
